INSECT DESTROYER

Darwin S. Karr, Los Angeles, Calif.

Application October 12, 1937, Serial No. 168,648

1 Claim. (Cl. 43—112)

This invention relates to novel and improved constructions in electric fly and insect destroyers and it consists in the constructions, arrangements and combinations herein described and claimed.

It is the cardinal purpose of the invention to provide a novel construction of grid, having an arcuate surface, facilitating and enticing flies and insects to alight thereon.

10 Is also an object of the invention to provide an insect destroyer of economical manufacture and highly sanitary in the provision of a removable tray for disposing of the destroyed insects.

15 Additional objects, advantages and features of invention will be apparent from the following description considered in conjunction with the accompanying drawings, wherein:

Figure 1 is a perspective view of a destroyer, constructed in accordance with my invention.

20 Figure 2 is an enlarged top plan view, parts being broken away.

Figure 3 is a sectional view, partly in section.

25 Figure 4 is a perspective view of a guard employed with the cage.

Figure 5 is an end elevation illustrating the guard installed.

In carrying out my invention, I provide a frame structure indicated at 10, which may be of any desired shape and size, although in the 30 present instance, this is shown as rectangular, and includes a lower horizontal flange 11 providing an open bottom and an upper flange 12, defining an opening in a cover which has a convex curvature, as may be seen from Figure 3.

35 The frame 10 is suitably supported by legs 13 at the longitudinal sides and as shown, the legs are formed from strap metal interconnected by a medial portion 14. The portion 14 may be raised from the supporting surface as shown, or 40 may extend in a plane flush with the lower end of the legs, as desired.

An insect collection tray 15 is provided, comprising lateral flanges 15' cooperable with the respective flanges 11 of the frame for support 45 thereof. The frame 10 is suitably apertured to admit the tray for seating engagement with the flanges and to permit ready withdrawal for emptying of the tray, as required.

50 An insulator bracket 16 is mounted upon an upright wall adjacent one end of the frame 10 and similar brackets 16' are secured to the frame adjacent the three remaining corners of the frame, the brackets 16—16' affording support for a grid 17. The grid in the present instance 55 comprises a series of transverse support rods

18 upon the upper surface of which and extended thereacross there are secured a plurality of closely spaced bars 19. Any suitable means may be employed for supporting the grid upon the brackets 16' but in the present instance, I have shown a binding screw 20. One or more of the adjacent bars 19 may be bent downwardly as at 20' and positioned behind the screw 20. Tightening of the screw will obviously secure the grid to the bracket. Two or more of the brackets 16' may be thus constructed, as found necessary. The grid 17 forms one electrode of a circuit whereby electrocution of insects may be accomplished, as will be apparent as the description proceeds.

The bracket 16 includes a suitable binding post or connection 20' for a lead 21 from a transformer 22, one side of which is grounded to the cover 23 for the frame. One or two of the bars 19 are electrically connected with the connection 20'. The cover 23 is suitably spaced from the grid 17 and upon the underside of the flange 12 there is secured by means of clamp screws 24 a grid 25, constructed similar to the grid 17, although the bars 19' will be in staggered relation with respect to the bars 19 of the grid 17.

The flange 12 and the cover 23 are convex, and the grids 17 and 25 will be similarly shaped, as may be seen in Figure 3, presenting a surface inducing flies and other insects to alight thereon 30 but the grids are spaced sufficiently close to permit the insects to complete the circuit when the insects crawl into engagement therebetween and both grids are contacted. The electrocuted insects will fall through the grids into the tray 15, 35 and the effluvia of previously killed flies and other insects is an irresistible attraction to other insects, obviating the necessity for baiting the destroyer.

When the tray has accumulated sufficient flies 40 and other insects, it may be readily withdrawn for cleaning.

In order that the trap may be harmless to persons who may come into contact therewith, I have provided a guard 26 illustrated in Figures 45 4 and 5.

The guard in the present instance, is formed from rod wire of any suitable gauge, and consists of a plurality of substantially U-shaped brace members 27, the downwardly extended legs 50 28 of which are connected to longitudinally extended parallel rods 29. The distance between the longitudinal rods is such as to readily span the sides of the frame 10, and at suitable points the frame 10 will be provided with tapped aper- 55

tures for reception of stove bolts which are also engaged through apertured clips 30 carried by the rods 29.

The U-shaped brace members 27 are substantially arcuate-shaped, conforming to the upper wall of the frame 10, being positioned a distance thereabove, and upon their upper edges a plurality of wire strands 31 are secured, the strands extending lengthwise thereacross and being spaced sufficiently close to prevent a person's hand, fingers, or other portions of the body from encountering either of the grids 17 or 25. The strands 31 may be arranged in multiples of three or otherwise, but in any event they should be arranged so as to not interfere with entrance of insects to the grids, and by arranging the guard as an open frame, ample entrance space is provided by which insects may gain access to the electrified grids.

20 It should be noted that the guard may be readily nested over the trap for shipping purposes.

It will be readily apparent that my destroyer is of such nature that it may be readily handled 25 by a person without liability of shock from the electric current since it will be impossible for a person to encounter both grids simultaneously,

as will be required, and while I have shown and described a specific embodiment of the invention, this is by way of illustration only, and I consider as my own all such modifications in structure as fairly fall within the scope of the 5 appended claim.

I claim:

An electrical insect destroyer comprising a box-like frame having an open bottom and a convex upper surface, the convex surface having a 10 opening formed therein, a grid secured and electrically grounded to the under side of the convex surface and positioned within the opening, the grid having a curvature corresponding to that of the convex surface of the frame, insulator brackets secured on opposed vertical walls of the frame below the grid, one of said brackets having a binding post for connection with an electromotive source, a second grid having a curvature corresponding to that of the first 15 named grid and spaced therebelow, said second named grid being positioned on the insulator brackets and electrically connected to the binding post, and certain of said brackets having a binding screw for clamping said second named 20 grid thereto.

DAR KARR.
